WIND DEFLECTOR

Hugh W. Shumaker, 517 S. Jackson St., Moscow, Idaho

Filed May 3, 1960, Ser. No. 60,440

Term of patent 14 years

(Cl. D14—6)

Fig. 1 is a rear perspective view of a wind deflector embodying my novel design.

Fig. 2 is a front perspective view thereof with a portion broken away for convenience of illustration only.

Fig. 3 is a top plan view thereof.

The fragmentary corner of a vehicle body shown in broken lines is included for illustrative purposes only.

I claim:

The ornamental design for a wind deflector, substantially as shown and described.
